UNITED STATES PATENT OFFICE.

CHRISTIAN C. HILL, OF CHICAGO, ILLINOIS, ASSIGNOR TO CLOTHILDE B. HILL, OF CHICAGO, ILLINOIS.

GRINDING AND POLISHING MACHINE.

No. 828,885.

Specification of Letters Patent.

Patented Aug. 21, 1906.

Application filed November 19, 1904. Serial No. 233,413.

To all whom it may concern:

Be it known that I, CHRISTIAN C. HILL, a citizen of the United States of America, and a resident of Chicago, in the county of Cook and State of Illinois, have invented certain new and useful Improvements in Grinding and Polishing Machines, of which the following is a specification.

The present invention relates to a machine for grinding and polishing lenses and other like convex or concave surfaces, and has for its object to provide a simple, durable, and efficient grinding or polishing mechanism capable of ready and accurate adjustment to produce a lens or other like surface having any required degree of convexity or concavity and which is especially adapted to produce any required form of what is known to optometrists as the "toric lens," all as will hereinafter more fully appear.

In the accompanying drawings, Figure 1 is a front elevation of a grinding and polishing machine embodying the present invention. Fig. 2 is a fragmentary vertical section of the same at line x x , Fig. 1. Fig. 3 is a fragmentary horizontal section at line x' x' , Fig. 2. Fig. 4 is a plan view of the machine. Fig. 5 is a fragmentary horizontal section at line x^2 x^2 , Fig. 1. Fig. 6 is a similar view at line x^3 x^3 , Fig. 1. Fig. 7 is an enlarged detail sectional elevation at line x^4 x^4 , Fig. 8, of the lens grinding or polishing and the lens-holding heads and their immediate connections. Fig. 8 is an end elevation of the same. Fig. 9 is a bottom view of the lens-carrying plate. Fig. 10 is a longitudinal section of the same at line x^5 x^5 , Fig. 9. Fig. 11 is an enlarged detail sectional elevation showing the parts in a reversed arrangement to that shown in Figs. 7 and 8; Fig. 12, a diagrammatic view showing the path of movement of one grinding member to the other. Fig. 13 is a perspective view of the machine, illustrating the general arrangement of the parts.

Similar numerals of reference indicate like parts in the several views.

Referring to the drawings, 1 is the supporting frame or base of the machine, and 2 a supporting post or upright secured thereto and forming a support for the journal-brackets, which pivotally support the radius-links of the grinding and polishing heads herein-after described. 3 and 4 represent a pair of substantially counterpart journal-brackets

arranged in angular relation to each other, as shown, and made vertically adjustable upon the sides of upright 1 in any usual and suitable manner. The particular construction shown in the drawings as illustrative of the adjustable connection of the journal-brackets to said post involves a construction as follows:

5 represents vertical undercut guide-grooves formed in the vertical post aforesaid.

6 represents clamping-bolts, the headed inner ends of which are adapted for engagement in the guide-grooves aforesaid.

7 represents clamping-nuts screwing upon the outer ends of said bolts and adapted to clamp the respective journal-brackets against the vertical post 1 at the required vertical adjustment of such brackets.

8 represents adjusting-rod arranged vertically in the undercut grooves 5 aforesaid. The upper ends of such rods are screw-threaded for operative engagement with the adjusting-nuts hereinafter described, while their lower portions are adapted for free vertical movement in vertical orifices formed therefor in the headed inner ends of the clamping-bolts 6, as illustrated in Figs. 2 and 3.

9 represents set-screws which screw axially through the bolts 6 and are adapted to bind the adjusting-rod 8 in the aforesaid orifices in the bolts 6 to effect a fixed engagement between said rods and said bolts.

10 represents adjusting-nuts engaging the screw-threaded upper ends of the adjusting-rod 8 and having abutment upon the top surface of the main post or upright 1. The said adjusting-nuts in connection with the adjusting-rod and set-screws aforesaid constitute precision adjustments for the journal-brackets, which in the construction shown are manually moved to approximately the required position, and after the engagement of the brackets with the adjusting-rod above set forth the final and precision adjustments are effected by the rotation of the adjusting-nuts 10. When so desired, scales or indexes may be provided upon the vertical faces of the post or upright 1 for the guidance of the operator in effecting the aforesaid adjustments of the journal-brackets.

11 and 12 are substantially counterpart oscillatory holding heads or sleeves in which the radius-links herein-after described are ad-

justably held. Such sleeves or heads are journaled horizontally and in angular relation to each other by means of horizontal arbors 13 and 14, fitting bearing-sleeves on the 5 journal-brackets, as shown more particularly in Figs. 1 and 4.

15 and 16 are set-screws passing axially through the arbors 13 and 14 for clamping the aforesaid radius-bars at the required 10 adjustment in the holding heads or sleeves aforesaid.

17 and 18 represent a pair of substantially counterpart radius-bars adjustable in a vertical direction in the holding heads or sleeves 15 aforesaid and free to oscillate upon the journal-axis of said sleeves in paths at substantially right angles to each other.

19 and 20 are horizontal members on the lower ends of the radius-bars for the support 20 of the respective grinding or polishing and the lens or work holding heads of the present construction, as hereinafter more fully set forth.

21 is the grinding or polishing head, and 25 22 the lens or work carrying head, both of which heads are provided with counterpart supporting-shanks by means of which the heads are secured to the horizontal members aforesaid in a readily-detachable manner and so that

30 various sizes of such heads may be used, but more especially with a view to a reversal of such heads in changing the operation of the machine from a production of convex surfaces to the production of concave surfaces, and 35 vice versa. In the first instance the lens or work holding head will be superimposed above the grinding or polishing head, as illustrated in Figs. 1, 7, and 8, while in the other instance the grinding or polishing head will 40 be superimposed above the lens or work holding head, as illustrated in Fig. 11.

23 is a sliding bar secured to the side of the horizontal member 19 and provided with a handled cam 24, by which its forward end 45 is forced against the side of the supporting-shank of the head 21 to hold the same in an open-sided holding-recess formed for the same in the side of said horizontal member, as shown in Figs. 1 and 6, the construction being adapted to permit a ready removal and 50 replacement of such head, as required.

25 is a clamping-screw passing through one branch of the yoke-shaped forward end of the upper horizontal member 20 and adapted to 55 engage against one side of the shank of the lens or work holding head to hold the same in an open-sided recess formed in the holding-block hereinafter described, the arrangement being adapted to permit a ready removal and 60 replacement of such head, as required.

26 is a holding-block, above referred to, pivotally connected by a horizontal bolt 27 to the other branch of the yoke-shaped forward end of the member 20 aforesaid, so as 65 to be capable of a pivotal adjustment in a

vertical plane and carrying with it in its adjustment the lens or work holding head 22, so that the surface of the lens operated upon will be ground away more to one end than the other, and thus meet a requirement of frequent occurrence in spectacle-lenses, where, owing to defective muscular convergence, it is desirable to give a prismatic form to the lenses. 70

28 is a vertical sector-shaped scale carried 75 by the horizontal member 20 for convenience in effecting the above-described adjustment of the lens or work holding head.

29 is a horizontal segmental scale carried 80 by the holding-block 26 in concentric relation to the axis of the lens or work holding head, and 30 is an index-arm carried by the shank of the head 22. The arrangement of the parts is such that the lens or work holding head 22 is capable of a pivotal adjustment in 85 a horizontal plane, so as to adapt the principal meridian of a toric spectacle-lens to a particular astigmatic condition of the eyes.

31 is the lens-holding plate, which in the present invention is formed with dovetail 90 side edges adapted for engagement in correspondingly-formed recesses in the opposed faces of a pair of depending cheeks 32 on the holding-head 22 aforesaid.

33 represents binding-screws passing 95 through the cheeks 32 and screwing into a transverse bar 34 for the purpose of drawing the cheeks 32 together and clamping the same upon the dovetail edges of the lens-holding plate aforesaid. 100

35 is a raised bearing-ridge upon the under surface of the said lens-holding plate, preferably of the circular form shown in Fig. 9 and against which the back of the lens or other piece of work operated upon has abutment to insure its correct alinement while the cement or like securing medium is being fused in the operation of cementing the lens to the lens-holding plate. 105

36 is an outer ridge upon the under surface 110 of the lens-holding plate, preferably of an elliptical shape corresponding with the elliptical form of a spectacle-lens and acting as a marginal guide in setting and cementing such lens in place. 115

37 is an annular gallery surrounding the grinding or polishing head 21 and having a dished form and a marginal upturned rim adapting it to contain the grinding or polishing material and to supply the same to the active grinding or polishing surfaces, as required in the normal movement or operation of the same. In the present improvement such gallery is formed of elastic india-rubber or like material adapting it for ready removal 120 and replacement upon the periphery of the head 21, and to such end the gallery will have a reinforced annular collar 38 for effecting a more substantial engagement, as illustrated in Figs. 1, 7, and 8. 125

39 and 40 are stationary guides on the main frame 1, having engagement with the lower ends of the respective radius-bars 17 and 18 to prevent lateral swaying of the same in actual use and maintain the same in their proper and respective rectilinear paths.

41 and 42 are pairs of shafts journaled at right angles to each other on the supporting base or frame 1 and geared together by bevel-gears 43 and 44, and a material part of the present invention consists in forming one of said bevel-gears with a less number of teeth than the other in order that a differential degree of rotation of said shafts will prevail and in that it has been found from extended practical experiment with such provision in connection with the oscillating movements of the respective heads 21 and 22, as heretofore described, that a constant change in the point of grinding or polishing contact takes place and that an extended period of time in the operation of the parts elapses before the same spot is again reached. In Fig. 12 a graphic illustration is given of the change of such grinding or polishing spot, as formed by a pencil or marker carried by the upper head 21, upon a sheet of paper carried by the lower head 22, the number of the teeth in the bevel-gears 43 and 44 being twenty-four and twenty-five, respectively.

45 and 46 are counterpart crank-disks carried by the shafts 41 and 42 aforesaid.

47 and 48 are adjustable wrist-pins carried by said crank-disks and having pitman connections 49 and 50 with the respective radius-bars 17 and 18, as illustrated in Figs. 1, 4, 5, and 6. By the independent adjustment of said wrist-pins the grinding or polishing zone is changed in either direction to suit the various widths, as well as lengths, of spectacle and like lenses operated upon, and such adjustments are of practical value, in that speedier effects can be obtained with the oscillations of the respective heads circumscribed to the extent of surface to be operated upon.

51 is the driving-pulley of the machine, carried by one of the pairs of shafts aforesaid.

52 represents collars adjustably secured to the radius-bars 17 and 18 and provided with vertical adjusting-screws 53, which in turn have abutment upon the oscillating holding-heads 11 and 12 and are adapted to afford a precision adjustment to said radius-bars in said heads, so that a limited vertical movement can be imparted to one radius-bar with relation to the other as the grinding operation progresses.

In the operation of the present invention the journal-brackets are initially adjusted upon the vertical post or upright of the machine by the adjusting means heretofore described and so that the active grinding or polishing surface of the respective heads carried at the lower ends of the radius-bars will

oscillate in arcs of the radius of the lens to be ground.

In the case of a spherical convex or concave lens such adjustments of the journal-brackets will be at a uniform height, while in the case of a toric lens the adjustment of said journal-brackets will vary to suit the two different curves of the two meridians of such lens.

With the adjustment of the journal-brackets as above described the mechanism is set in motion, the grinding or polishing material mixed with water or other fluid being fed by hand to the gallery 37 of the lowermost of the lens-forming heads and by such gallery supplied to the active grinding-surfaces of the heads, as required.

Having thus fully described my said invention, what I claim as new, and desire to secure by Letters Patent, is—

1. In a grinding or polishing machine, the combination of a support, journal-brackets attached to said support, a pair of radius-bars oscillating on said brackets in vertical planes transverse to each other, a grinding or polishing head arranged at the lower end of one of said radius-bars, an opposed work-carrying head arranged at the lower end of the other radius-bar, and means for imparting oscillatory movements to said radius-bars.

2. In a grinding or polishing machine, the combination of a support, journal-brackets attached to said support, a pair of radius-bars oscillating on said brackets in vertical planes transverse to each other, a grinding or polishing head arranged at the lower end of one of said radius-bars, an opposed work-carrying head arranged at the lower end of the other radius-bar, and means for imparting differential oscillatory movements to said radius-bars.

3. In a grinding or polishing machine, the combination of a support, journal-brackets attached to said support, a pair of radius-bars oscillating on said brackets in vertical planes transverse to each other, a grinding or polishing head arranged at the lower end of one of said radius-bars, an opposed work-carrying head arranged at the lower end of the other radius-bar, and means for imparting oscillatory movements to said radius-bars, the same comprising a pair of driving-shafts, gear connections between said shafts, and means for transforming the rotary motion of said shafts into oscillatory motions of the respective radius-bars.

4. In a grinding or polishing machine, the combination of a support, journal-brackets attached to said support, a pair of radius-bars oscillating on said brackets in vertical planes transverse to each other, a grinding or polishing head arranged at the lower end of one of said radius-bars, an opposed work-carrying head arranged at the lower end of the other radius-bar, and means for imparting

1 differential oscillatory movements to said radius-bars, the same comprising a pair of driving-shafts, gear connections between said shafts having a different number of teeth, and means for transforming the rotary motion of said shafts into oscillatory motions of the respective radius-bars.

5. In a grinding or polishing machine, the combination of a support, journal-brackets attached to said support, a pair of radius-bars oscillating on said brackets in vertical planes transverse to each other, a grinding or polishing head arranged at the lower end of one of said radius-bars, an opposed work-carrying head arranged at the lower end of the other radius-bar, and means for imparting oscillatory movements to said radius-bars, the same comprising a pair of driving-shafts, gear connections between said shafts, crank-disks on said shafts, wrist-pins on said disks, and pitman connections between said wrist-pins and the respective radius-bars.

6. In a grinding or polishing machine, the combination of a support, journal-brackets attached to said support, a pair of radius-bars oscillating on said brackets in vertical planes transverse to each other, a grinding or polishing head arranged at the lower end of one of said radius-bars, an opposed work-carrying head arranged at the lower end of the other radius-bar, and means for imparting differential oscillatory movements to said radius-bars, the same comprising a pair of driving-shafts, gear connections between said shafts having a different number of teeth, and means for transforming the rotary motion of said shafts into oscillatory motions of the respective radius-bars.

7. In a grinding or polishing machine, the combination of a support, a pair of journal-brackets made vertically adjustable on said support, a pair of radius-bars oscillating on said brackets in vertical planes transverse to each other, a grinding or polishing head arranged at the lower end of one of said radius-bars, an opposed work-carrying head arranged at the lower end of the other radius-bar, and means for imparting oscillatory movements to said radius-bars.

8. In a grinding or polishing machine, the combination of a support, a pair of journal-brackets made vertically adjustable on said support, a pair of radius-bars oscillating on said brackets in vertical planes transverse to each other, a grinding or polishing head arranged at the lower end of one of said radius-bars, an opposed work-carrying head arranged at the lower end of the other radius-bar, and means for imparting differential oscillatory movements to said radius-bars.

9. In a grinding or polishing machine, the combination of a support, a pair of journal-brackets made vertically adjustable on said support, a pair of radius-bars oscillating on

70 said brackets in vertical planes transverse to each other, a grinding or polishing head arranged at the lower end of one of said radius-bars, an opposed work-carrying head arranged at the lower end of the other radius-bar, and means for imparting oscillatory movements to said radius-bars, the same comprising a pair of driving-shafts, gear connections between said shafts, and means for transforming the rotary motion of said shafts 75 into oscillatory motions of the respective radius-bars.

10. In a grinding or polishing machine, the combination of a support, a pair of journal-brackets made vertically adjustable on said support, a pair of radius-bars oscillating on said brackets in vertical planes transverse to each other, a grinding or polishing head arranged at the lower end of one of said radius-bars, an opposed work-carrying head arranged at the lower end of the other radius-link, and means for imparting differential oscillatory movements to said radius-bars, the same comprising a pair of driving-shafts, gear connections between said shafts having 80 a different number of teeth, and means for transforming the rotary motion of said shafts into oscillatory motions of the respective radius-bars.

85 11. In a grinding or polishing machine, the combination of a support, a pair of journal-brackets made vertically adjustable on said support, a pair of radius-bars oscillating on said brackets in vertical planes transverse to each other, a grinding or polishing head arranged at the lower end of one of said radius-bars, an opposed work-carrying head arranged at the lower end of the other radius-link, and means for imparting oscillatory movements to said radius-bars, the same comprising a pair of driving-shafts, gear connections between said shafts having 90 a different number of teeth, and means for transforming the rotary motion of said shafts into oscillatory motions of the respective radius-bars.

95 12. In a grinding or polishing machine, the combination of a support, a pair of journal-brackets made vertically adjustable on said support, a pair of radius-bars oscillating on said brackets in vertical planes transverse to each other, a grinding or polishing head arranged at the lower end of one of said radius-bars, an opposed work-carrying head arranged at the lower end of the other radius-link, and means for imparting differential oscillatory movements to said radius-bars, the same comprising a pair of driving-shafts, gear connections between said shafts having a different number of teeth, crank-disks on 100 said shafts, wrist-pins on said disks, and pitman connections between said wrist-pins and the respective radius-bars.

13. In a grinding or polishing machine, the combination of a support, journal-brackets attached to said support, a pair of radius-

6
ranged at the lower end of one of said radius-bars, an opposed work-carrying head arranged at the lower end of the radius-bar, means for imparting oscillatory movements to said radius-bars, and means for effecting a limited vertical adjustment of one radius-bar with relation to the other.

24. In a grinding or polishing machine, the combination of a support, a pair of journal-brackets made vertically adjustable on said support, a pair of radius-bars oscillating on said brackets in vertical planes transverse to each other, a grinding or polishing head arranged at the lower end of one of said radius-bars, an opposed work-carrying head arranged at the lower end of the other radius-bar, means for imparting differential oscillatory movements to said radius-bars, and means for effecting a limited vertical adjustment of one radius-bar with relation to the other.

25. In a grinding or polishing machine, the combination of a support, journal-brackets attached to said support, a pair of radius-bars oscillating on said brackets in vertical planes transverse to each other, a grinding or polishing head arranged at the lower end of one of said radius-bars, an opposed work-carrying head arranged at the lower end of the other radius-bar, means for imparting oscillatory movements to said radius-bars, and means for guiding the lower ends of the radius-bars in rectilinear paths.

26. In a grinding or polishing machine, the combination of a support, journal-brackets attached to said support, a pair of radius-bars oscillating on said brackets in vertical planes transverse to each other, a grinding or polishing head arranged at the lower end of one of said radius-bars, an opposed work-carrying head arranged at the lower end of the other radius-bar, means for imparting differential oscillatory movements to said radius-bars, and means for guiding the lower ends of the radius-bars in rectilinear paths.

27. In a grinding or polishing machine, the combination of a support, a pair of journal-brackets made vertically adjustable on said support, a pair of radius-bars oscillating on said brackets in vertical planes transverse to each other, a grinding or polishing head arranged at the lower end of one of said radius-bars, an opposed work-carrying head arranged at the lower end of the other radius-bar, means for imparting oscillatory movements to said radius-bars, and means for guiding the lower ends of the radius-bars in rectilinear paths.

28. In a grinding or polishing machine, the combination of a support, a pair of journal-brackets made vertically adjustable on said support, a pair of radius-bars oscillating on said brackets in vertical planes transverse to each other, a grinding or polishing head arranged at the lower end of one of said radius-

bars, an opposed work-carrying head arranged at the lower end of the other radius-bar, means for imparting differential oscillatory movements to said radius-bars, and means for guiding the lower ends of the radius-links in rectilinear paths.

29. In a grinding or polishing machine of the character herein described, the combination of a work-holding head, and a work-carrying plate provided with a bearing-ridge on its face.

30. In a grinding or polishing machine of the character herein described, the combination of a work-holding head, and a work-carrying head provided with a bearing-ridge and an annular guiding-ridge on its face.

31. In a grinding or polishing machine of the character herein described, the combination of a work-holding head, side cheeks on said head having beveled recesses in their opposed faces, a work-carrying plate having beveled edges, and means for clamping said cheeks upon the beveled edges of said plate.

32. In a grinding or polishing machine of the character herein described, the combination of a work-holding head, side cheeks on said head having beveled recesses in their opposed faces, a work-carrying plate having beveled edges, and means for clamping said cheeks upon the beveled edges of said plate, the same comprising screws passing through said cheeks, and a transverse bar receiving said screws.

33. In a grinding or polishing machine of the character herein described, the combination with the grinding or polishing and work-holding heads arranged in apposition, of a gallery secured to the lowermost head in a plane with the upper surface of said head and provided with an upturned margin.

34. In a grinding or polishing machine of the character herein described, the combination with the grinding or polishing and work-holding heads arranged in apposition, of an elastic gallery secured to the lowermost head in a plane with the upper surface of said head and provided with an upturned margin.

35. In a grinding or polishing machine of the character herein described, the combination with the grinding or polishing and work-holding heads arranged in apposition, of an elastic gallery secured to the lowermost head in a plane with the upper surface of said head and provided with an upturned margin and a reinforced annular collar.

36. In a grinding or polishing machine, the combination of a grinding-head, a work-holding head, and means for imparting differential reciprocation to said heads in directions transverse to each other, the same comprising a pair of driving-shafts, gear connections between said shafts having a different number of teeth, and means for transforming the rotary motion of said shafts into reciprocating motions of said heads.

37. In a grinding or polishing machine, the combination of a grinding-head, a work-holding head, and means for imparting differential reciprocation to said heads in directions transverse to each other, the same comprising a pair of driving-shafts, gear connections between said shafts having a different number of teeth, crank-disks on said shafts, and

pitman connections between said crank-disks and the respective heads.

Signed at Chicago, Illinois, this 14th day of November, 1904.

CHRISTIAN C. HILL.
